UNITED STATES PATENT OFFICE.

WILLIAM M. SMITH, OF WEST MERIDEN, CONNECTICUT, ASSIGNOR TO THE
MERIDEN BRITANNIA COMPANY, OF SAME PLACE.

DESIGN FOR BURIAL-CASKET HANDLE-SOCKET.

Specification forming part of Design No. **7,103**, dated January 6, 1874; application filed December 27, 1873.
[Term of Patent 7 years.]

To all whom it may concern:

Be it known that I, WILLIAM M. SMITH, of West Meriden, in the county of New Haven and State of Connecticut, have invented a new Design for Casket-Handle Socket; and I do hereby declare the following, when taken in connection with the accompanying drawing and the letters of reference marked thereon, to be a full, clear, and exact description of the same, and which said drawing constitutes part of this specification, and represents a front view.

This invention relates to a design for that part of a coffin or casket handle termed the "socket"—that is, the portion to which the handle is pivoted, and by which it is secured to the casket—a pair of these sockets being used for each handle. The invention consists in the peculiar configuration or outline of the socket, as shown in the accompanying illustration, and which I will now proceed to describe.

The base is substantially flat upon its surface, with the lug A formed thereon to receive the handle, the form of this lug being no part of this design. The plate terminates, at the top and bottom, in a point, presenting angles *a* *b* *b*, and upon one side a projection is formed, with similar angles. The other edge, which is, to a great extent, hidden, may be straight or curved.

The surface of the plate is shown as with an edge-border in relief; but my design is confined to the outline of the plate upon the three sides described.

I claim as my invention—

The design for casket-handle socket, as herein described, and shown in the accompanying drawing.

WILLIAM M. SMITH.
